COMBINED COLLAPSIBLE TUBE DISPENSER AND CAP

Sheldon David Hulsh, 530 Park Ave., New York, N.Y.

Filed May 7, 1959, Ser. No. 55,811

Term of patent 14 years

(Cl. D58—17)

Figure 1 is a front elevational view of a combined collapsible tube dispenser and cap showing my new design;

Figure 2 is a side elevational view thereof; and

Figure 3 is a perspective view showing the cap of the dispenser removed from the dispenser.

I claim:

The ornamental design for a combined collapsible tube dispenser and cap substantially as shown.
